UNITED STATES PATENT OFFICE.

JOSEPH BECK, OF ST. LOUIS, MISSOURI.

DESIGN FOR A FLOWER-STAND.

SPECIFICATION forming part of Design No. 34,091, dated February 12, 1901.

Application filed January 21, 1901. Serial No. 44,227. Term of patent 7 years.

To all whom it may concern:

Be it known that I, JOSEPH BECK, of the city of St. Louis, State of Missouri, have invented and produced a new and original Design for a Flower-Stand, of which the following is a full, clear, and exact description, reference being had to the accompanying drawings, forming a part hereof.

Figure 1 is a side elevation showing my complete design. Fig. 2 is a bottom view.

As shown in the drawings, the material feature of my invention consists of a vertical standard having a series of knobs rigid therewith and mounted upon a base consisting of a series of radial arms having knobs formed thereon and an ornamented receptacle mounted upon the top of the said standard.

Referring to the drawings in detail, 1 denotes a vertical standard, formed rigid with 20 which is a series of knobs 2, and between each

adjacent pair of knobs is a flange or enlargement 3. A groove 4 is formed in each of the said knobs 2.

5 indicates the radial arms forming the base, and integral with each of said arms is 25 a series of knobs 6, between which upon the arms 5 are flanges 7. The arms 5 are fixed to a common center 8, the same being connected to the lower end of the vertical standard 1. Upon the top of the standard 1 is a receptacle 9.

I claim—

The design for a flower-stand, substantially as herein shown and described.

In testimony whereof I affix my signature 35 in presence of two witnesses.

JOSEPH BECK.
